MOTOR

Filed Sept. 26, 1923

UNITED STATES PATENT OFFICE.

CHARLES H. ALLEN, OF CLAREMONT, NEW HAMPSHIRE, ASSIGNOR TO SULLIVAN.
MACHINERY COMPANY, A CORPORATION OF MASSACHUSETTS.

MOTOR.

Application filed September 26, 1923. Serial No. 664,858.

My invention relates to motors.

An object of my invention is to provide an improved motor and more particularly a motor of the fluid pressure percussive type especially adapted for use with drill sharpeners. Another object of my invention is to provide an improved motor in which extreme rapidity of reciprocation may be obtained. A further object of my invention is to provide an improved motor for drill sharpening purposes in which by reason of increase in speed of reciprocation of the piston, the speed of drill sharpening is materially increased. A still further object of my invention is to provide an improved motor having means for materially increasing its speed and for preventing the stalling of the motor under certain conditions. These and other objects and advantages of my invention will hereinafter more fully appear.

In the accompanying drawings I have shown for purposes of illustration three forms which my invention may assume in practice.

25 In these drawings,—

Fig. 1 is a central longitudinal sectional view of a fluid pressure percussive type motor in which the illustrative embodiment of my invention is incorporated, the piston being shown in a forward position and the striking pin in its extreme rearward position.

Fig. 2 is a view similar to that shown in Fig. 1 with the piston in an extreme rearward position and the striking pin in its extreme forward position.

Fig. 3 is a modified form of the piston shown in Figs. 1 and 2.

Fig. 4 is a further modified form of the 40 piston and cylinder shown in Figs. 1 and 2.

In the form of my invention shown for purposes of illustration in the accompanying drawings, I have provided a cylinder 1 having a bore 2 in which a piston 3 is reciprocable and adapted to percussively actuate a striking pin 4 carried by the front end of the motor. The piston 3 is provided with spaced front and rear heads 5 and 6 respectively and which heads are connected by a reduced portion 7 forming an annular space 8 in the cylinder. The opposite ends of the cylinder are closed by suitable head members 9 and 10 which are held in the desired assembled relation by means of side rods

including bolt heads or nuts 11, one of which 55 is shown herein, in a well known manner.

In order to distribute motive fluid to and to conduct away exhaust from the opposite ends of the cylinder, suitable distribution passages 12 and 13 lead to points adjacent the opposite ends of the cylinder, the passage 12 leading herein to the front end of the cylinder while the passage 13 leads to the rear end thereof. The supply and exhaust of fluid through the distribution passages 12 and 13 is controlled by a valve mechanism which is generally designated by 14 and which comprises a casing 15 in which suitable bushings 16 are so arranged as to form a chamber having end portions 17 of slightly 70 smaller diameter than its central portion 18. The passages 12 and 13 communicate with the valve chamber adjacent the ends of the central enlarged bore 18, the passage 12 communicating as at 19 and terminating in an annular groove 20, and the passage 13 communicating as at 21 and terminating in an annular groove 22, these grooves being formed adjacent shoulders 23 which constitute the ends of the enlarged bore 18. 75 Near the remote ends of the smaller bores 17, ports 24 and 25 connect throwing passages 26 and 27 with the valve chamber, these passages at their opposite ends communicating with the bore of the cylinder 2. The passage 26 communicates with the cylinder at a point spaced a relatively short distance from the position of the rear end of the piston when the latter is in its forward working position by a port 28 and the passage 27 80 opens in the bore of the cylinder a substantial distance to the front from the middle thereof, through a port 29. Intermediate the ports 19 and 24 and 21 and 25 respectively in the valve chest, there are formed 85 annular grooves 30 and 31, which grooves communicate by ports 32 and 33 with chambers 34 and 35 communicating with the atmosphere. It will be noted that the heads 5 and 6 of the piston 3 are provided with 90 grooves 36 and 37 and slots or passages 38 and 39 connecting said grooves with the annular chamber 8 formed between the piston heads. It will also be noted that a port 40 is provided substantially intermediate the 95 ends of the cylinder 2, which is connected at certain times with the annular space 8. A groove 41 is provided in the rear end of the 100 105

piston head 6 and this groove communicates with the rear end of the cylinder bore by means of a passage 42 for purposes herein-after more fully described.

Within the valve chest is a valve which is of the three spool type, herein generally designated 43, and comprising end spools or heads 44 and 45 fitting in the smaller bores 17 and a central spool 46 of slightly larger diameter fitting in the larger bore 18, the heads 44 and 45 being respectively connected with the spool 46 by reduced portions 47 and 48. The end spools 44 and 45 engage buffers 49 and 50 arranged within the ends of the bushings 16. A fluid pressure supply port communicates with an annular groove 52 formed between the ends of the bushings 16 in the central part of the valve chest.

In the form of my invention shown in Fig. 3, it will be noted that instead of grooving and slotting the rear end of the piston as at 41 and 42, the outside diameter of the head 6 is ground down slightly for a short part of its length as at 53. The function of this reduced portion is substantially the same as that of the slot and groove shown in Figs. 1 and 2.

In the form of my invention shown in Fig. 4, it will be noted that instead of grooving the rear end of the piston 3 as at 41, the bore 2 of the cylinder is provided with a longitudinally extending groove 54. This groove functions in a manner similar to that of the groove 41 or the reduced diameter of portion 53.

Having described the structure of the illustrative form of my invention, I will now point out its mode of operation. Assuming the parts to be in position shown in Fig. 1 with the piston against the striking pin and the valve held in position against the rear buffer 50 by means of live fluid pressure acting on the right hand side of the spool 46, it will be observed that the motive fluid is passing from the annular space 52 to the right of the head 46 and, by way of port 19 and the passage 12 to the front end of the piston 3 to cause a rearward movement thereof. Simultaneously the rear end of the piston is connected to exhaust by way of passage 13, port 21, port 33, and chamber 35 which communicates with the atmosphere, the rearward end of the valve exhausting through the port 25, throwing passage 27, port 29, groove 36 formed in the head 5 of the piston, passage 38, annular chamber 8, and port 40 to the atmosphere. The piston 3 will accordingly move rearwardly. When the piston reaches its rearward position the operation is reversed. When the piston 3 moves forward during the normal running of the motor only a puff of air is admitted through the groove 41 and throwing passage 26 to the forward end of the valve preliminarily filling the throwing passage and the

area in front of the valve with live fluid pressure, thereby permitting a more rapid action of the valve when the throwing passage is uncovered by the rear end of the piston. Heretofore when the striking pin 4 was in its extreme rearward position, as shown in Fig. 1, communication between the cylinder and the throwing passages 26 and 27 was cut off by the piston heads 5 and 6. However, if the motor stalls with the groove 41 in communication with the throwing passage 26 (see Fig. 1), the pressure passes from the rear end of the piston through the groove 41 and the port 26 and builds up in front of the valve head 44 throwing the valve and reversing the operation of the piston, thereby preventing the consequent stalling of the piston at this point if the groove 41 were not present. The groove 41 also permits the starting of the motor when the piston is in its extreme rearward position (see Fig. 2), the passage 13 being ordinarily cut off when such a groove is not present.

As a result of my improvement it will be observed that the possibility of stalling the motor as heretofore experienced, that is when the striking pin 4 is in its extreme rearward position with both throwing passages 26 and 27 covered by the piston heads 5 and 6, is entirely eliminated, one of the throwing passages being uncovered at that time, and my improvement also provides means whereby the action of the valve is speeded up, consequently increasing the speed of the piston and the power of the motor. As for an example of the efficacy of this auxiliary groove it may be stated that an improvement of substantially ten per cent in speed was observed over a similar motor constructed without this change.

While I have in this application specifically described three forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a pressure fluid actuated motor, a cylinder, a piston reciprocable therein, means forming fluid distribution passages communicating with said cylinder, a valve controlling said passages, valve throwing means including means forming throwing passages opening into said cylinder for admitting live pressure fluid to the ends of said valve for throwing the latter during normal operation of the motor, and a movable abutment adapted to be actuated by said piston, said valve throwing means also including means for admitting live pres- 130

sure fluid to one end of said valve when movement of said piston is so limited by movement of said abutment to one extreme position of the latter that the piston overlies the communication of the corresponding throwing passage with the cylinder.

2. In a pressure fluid actuated motor, a cylinder, a piston reciprocable therein, means forming fluid distribution passages communicating with said cylinder, a valve controlling said passages, valve throwing means including means forming throwing passages for admitting live pressure fluid to the ends of said valve for throwing the latter during normal operation of the motor, and a movable abutment adapted to be actuated by said piston, said valve throwing means also including a fluid conducting passage formed in said piston and communicable with one of said valve throwing passages when movement of said piston is limited by movement of said abutment to one extreme position of the latter.

3. In a pressure fluid actuated motor, a cylinder, a piston reciprocable therein, means forming fluid distribution passages communicating with said cylinder, a valve controlling said passages, valve throwing means including means forming throwing passages opening into said cylinder for admitting live pressure fluid to the ends of said valve for throwing the latter during normal operation of the motor, and a reciprocable abutment adapted to be actuated by said piston, said valve throwing means also including means for maintaining communication between said cylinder and one end of said valve when movement of said piston is so limited by movement of said abutment to one extreme position of the latter that the piston overlies the communication of the corresponding throwing passage with the cylinder.

4. In a pressure fluid actuated motor, a cylinder, a piston reciprocable therein, means forming fluid distribution passages communicating with said cylinder, a valve controlling said passages, valve throwing means including means forming throwing passages opening into said cylinder for admitting live pressure fluid to the ends of said valve for throwing the latter during normal operation of the motor, and a reciprocable abutment adapted to be actuated by said piston, said valve throwing means also including means for maintaining communication between said cylinder and one end of said valve when movement of said piston is so limited by movement of said abutment to its extreme rearward position that the piston overlies the communication of the corresponding throwing passage with the cylinder.

5. In a pressure fluid actuated motor, a cylinder, a piston reciprocable therein, means forming fluid distribution passages commu-

nicating with said cylinder, a valve controlling said passages, valve throwing means including means forming throwing passages for admitting live pressure fluid from said cylinder to the ends of said valve for throwing the latter during normal operation of the motor, and a reciprocable abutment adapted to be actuated by said piston, said valve throwing means also including fluid conducting passages formed in said piston and communicating with one of said throwing passages for maintaining communication between said cylinder and one end of said valve when movement of said piston is limited by movement of said abutment to its extreme rearward position.

6. In a pressure fluid actuated motor, a cylinder, a piston reciprocable therein having spaced piston heads, means forming fluid distribution passages communicating with said cylinder, a valve controlling said passages, valve throwing means including means forming throwing passages for admitting live pressure fluid from said cylinder to the ends of said valve for throwing the latter during normal operation of the motor, and a reciprocable abutment adapted to be actuated by said piston, said valve throwing means also including a circumferentially extending fluid conducting groove formed in one of said piston heads and communicating with one of said throwing passages for maintaining communication between said cylinder and one end of said valve when movement of said piston is limited by movement of said abutment to its extreme rearward position.

7. In a pressure fluid actuated motor, a cylinder, a piston reciprocable therein, means forming fluid distribution passages communicating with the opposite ends of said cylinder, a valve controlling said passages and having opposed pressure areas, valve throwing means including means forming throwing passages for admitting live pressure fluid from the opposite ends of said cylinder respectively to said pressure areas for throwing said valve during normal operation of the motor, and a reciprocable abutment adapted to be actuated by said piston, said valve throwing means also including fluid conducting passages formed in said piston for maintaining communication respectively with the rear end of said cylinder and the forward pressure area of said valve when movement of said piston is limited by movement of said abutment to its extreme rearward position.

8. In a pressure fluid actuated motor, a cylinder, a piston reciprocable therein, fluid distribution means therefor including a distribution valve, a reciprocable abutment adapted to be actuated by said piston, and means cooperating with said fluid distribution means including fluid conducting pas-

sages formed in said piston to supply motive fluid to the front end of the valve for preventing stalling of the piston when said abutment is in its extreme rearward position.

9. In a pressure fluid actuated motor, a cylinder, a piston reciprocable therein, means forming fluid distribution passages communicating with said cylinder, a valve controlling said passages, valve throwing means including means forming throwing passages opening into said cylinder for admitting live pressure fluid to the ends of said valve for throwing the latter during normal operation of the motor, and a movable abutment adapted to be actuated by said piston, said valve throwing means also including means for admitting live pressure fluid to one end of said valve when the piston overlies the communication of the corresponding throwing passage with the cylinder, said latter means being dependent upon one extreme position of said abutment and operative to start the motor when said abutment is in its extreme position.

10. In a pressure fluid actuated motor, a cylinder, a piston reciprocable therein, means forming fluid distribution passages communicating with said cylinder adjacent the ends thereof, a valve controlling said passages, and means for throwing said valve by the action of fluid pressure in the cylinder.

der between the piston and the cylinder head comprising throwing passages communicating respectively with the cylinder and the opposite ends of said valve, said valve throwing means also including fluid conducting passages formed in the piston for preliminarily supplying live pressure fluid to one of said throwing passages prior to its being overrun by an outer end of the piston to admit throwing pressure thereto.

11. In a pressure fluid actuated motor, a cylinder, a piston reciprocable therein, means forming fluid distribution passages communicating with said cylinder adjacent the ends thereof, a valve controlling said passages, and means for throwing said valve by the fluid in the cylinder which directly actuates the piston comprising throwing passages communicating respectively with the cylinder and the opposite ends of said valve, said valve throwing means also including a circumferentially extending fluid conducting groove formed on the periphery of said piston and communicable respectively with one end of said cylinder and one of said throwing passages for preliminarily admitting live pressure fluid to one of the latter prior to the admission of throwing pressure thereto.

In testimony whereof I affix my signature.
CHARLES H. ALLEN.
